(57) **CLAIM**

The ornamental design for a wall base with groove and curved lower section, as shown and described.

DESCRIPTION

FIG. 1 is a perspective view of the wall base with groove and curved lower section, according to the invention;

FIG. 2 is a top end view of the wall base with groove and curved lower section shown in FIG. 1;

FIG. 3 is a front view of the wall base with groove and curved lower section shown in FIG. 1;

FIG. 4 is a side view of the wall base with groove and curved lower section shown in FIG. 1;

FIG. 5 is a rear view of the wall base with groove and curved lower section shown in FIG. 1;

FIG. 6 is a side view of the wall base with groove and curved lower section shown in FIG. 1, shown from the opposite side of that shown in FIG. 4; and,

FIG. 7 is a bottom end view of the wall base with groove and curved lower section shown in FIG. 1.

The wall base with groove and curved lower section is shown with a symbolic break in its length. The appearance of any portion of the wall base with groove and curved lower section between the break lines forms no part of the claimed design.
